IMPULSE SENDER

Theodore C. Riebe, Chicago, Ill., assignor to
 Automatic Electric Laboratories, Inc., Chicago,
 Ill., a corporation of Delaware

Application January 24, 1947, Serial No. 724,030

10 Claims. (Cl. 177—380)

1

The present invention relates in general to impulse transmitters using an impulser similar to the well known calling device used in automatic telephone systems, but modified therefrom.

The illustrated embodiment discloses the invention as used in a telephone system for identifying the calling station on a multi-station line.

The principal object of the invention is to provide an impulse transmitter of simple and rugged construction adapted for use in identifying the calling station in various communication and signalling systems.

Another object is to provide a push button controlled impulse transmitter for transmitting a predetermined number of impulses for the purpose of identifying the calling station on a multi-station line and in which the mechanism of the transmitter is so designed that regardless of the manipulations of the push button, the transmitter can only transmit a number of impulses corresponding to the calling station.

A feature of the invention relates to the arrangement whereby impulses will only be transmitted in response to a full stroke operation of the push button, whereas, partial operations are ineffective to operate the impulse transmitting mechanism.

Another feature of the invention relates to the mechanism, whereby, in response to a full stroke of the push button, the impulse cam wheel of the transmitter always makes one full revolution and no more.

Another feature of the invention relates to the interlocking arrangement, whereby, after initiation of the impulse cam it is impossible to reactivate the push button until the impulse cam has completed its full revolution, thus preventing a calling station from sending a false calling station identification signal.

The objects and features set forth above are attained in accordance with the present invention by providing an impulse transmitting device comprising a main rotatable shaft, a spring motor mounted over the shaft, a drive gear mounted on the shaft and free to turn about the shaft in one direction, but locked to the shaft during movement in the opposite direction, a finger-operated push bar operatively connected to the shaft, whereby as the push bar is moved inward, the shaft is rotated in one direction and the spring motor is wound, after the push bar has restored to normal the spring motor unwinds and the shaft is rotated in the opposite direction, an auxiliary shaft geared directly to the drive gear and containing an impulse wheel mounted thereon,

2

whereby, the impulse wheel is rotated as the drive gear turns, the device also comprises a holding means consisting of three holding pawls functioning at different intervals during a cycle of operation for preventing incomplete operation and false transmission signals.

The invention is illustrated in the accompanying drawings, comprising Figures 1 to 5 inclusive, which are described as follows:

- 10 Figure 1 is a side view as shown from the left.
 Figure 2 is a side view as shown from the right.
 Figure 3 is a partial end view as shown from the front.
 Figure 4 is an exploded view showing the relative positions of the mechanism on the right side.
 Figure 5 is a fragmentary view showing the push bar moved to its limit and also showing the dotted portion shown in Figure 2.
 It will be noted that some of the illustrated mechanisms such as the governor, spring motor, shunt springs, impulse springs, and cam, are shown in U. S. Patent 1,642,822 granted September 30, 1927 to Herbert F. Obergfell.

Referring now to the drawings showing the impulse transmitter, Figure 1 shows the frame 1, upon which is mounted contact arm support 2, impulse wheel support 3, spring motor support 4, and worm gear support 5. Impulse springs 14 and 15, and shunt springs 11, 12 and 13 are mounted on support 2. Impulse wheel 17, containing teeth such as 18, is mounted on support 3. Shunt spring cam 8 is secured to one end of spring motor 9 and the two are placed over and secured to a slot in rotatable shaft 28. The other end of spring 9 is hooked to a raised catch 58 on support 4. Insulating control member 10 actuated by cam 8, is carried on shunt spring 11. Worm gear 7, meshing with teeth on governor 16, is mounted on a shaft and rotatably secured to support 5.

In Figure 2, push bar 19 is slidably mounted at one end to frame 1 through a slot provided in frame 1. The other end slides through a slot in plate 47 which is secured to the frame 1. Push bar 19 contains stops 57 and 59, a release pin 29, and a notch 55. Holding pawl 22 is mounted on pivot 38 which is secured to frame 1, and biased by spring 23, one end of which is secured to support post 35. A notch 34 is provided in push bar 19 for pawl 22 to engage. A linkage plate 30 is rotatably mounted on shaft 28 by means of screw 53, and hub 54. It carries linkage pin 40, linkage spring 24, and spring support post 46. The other end of spring 24 is fastened to support post 36 on frame 1. Linkage pin 40 engages notch

55 of push bar 19. Governor brake drum 6 is secured to governor support 26, which is fastened to frame 1. Bracket 27, secured to frame 1, is the support for the worm gear and impulse wheel shaft. Holding pawl 20 is mounted on pivot 39 which is secured to frame 1, and biased by spring 25 one end of which is secured to support post 37. Holding pawl 20 includes a notch which may engage a tooth such as 50 in holding gear 49. Holding pawl 21 is mounted on pivot 41 which is secured to frame 1, and is biased by spring 43 one end of which is secured to support post 45. Control plate 31 is mounted over and secured to shaft 28 and is located underneath linkage plate 30. Control plate 31 contains release pin 51 for actuating holding pawl 21, mounting pivot 42 for mounting pawl 43 on plate 31, support post 45 for biasing pawl 43, release finger 33 for releasing pawl 22, and an indentation in a portion of its periphery to allow linkage plate 30 to return to normal independent of plate 31.

In Figure 4, drive gear 32 is located below holding gear 49, which is below movable pawl gear 52, all of them constituting an integral unit mounted over shaft 28 and free to rotate thereon. Movable pawl 43 is mounted on pivot 42 which is secured to control plate 31 and biased by spring 44, one end of which is secured to support post 45. Teeth such as 56 in movable pawl gear 52 are provided for the engagement therewith by the movable pawl 43.

Having given a description as to construction of the various parts of the impulse transmitter, a brief description will now be given of the operations which take place in response to the depression and restoration of the push bar 19.

Referring mainly to Figures 2 and 5, as push bar 19 starts its depression to the right, its release pin 29 moves away from holding pawl 20, and allows the pawl 20 to be actuated by spring 25 to drop into a tooth such as 50 in holding gear 49, but it does not mesh tightly and leaves a space between the two as shown in Figure 5. Linkage pin 40 in linkage plate 30 stays within notch 55 of push bar 19 at all times, therefore, a depression of the push bar 19 will cause the linkage plate 30 to rotate clockwise. Linkage pin 40 also extends down and bears against a side of the indented portion of the periphery of control plate 31 so that a rotation of linkage plate 30 will cause a similar rotation of the control plate 31. As control plate 31 is rotated, shaft 28 rotates, and shunt cam 8 no longer bears against insulating control member 10, thereby allowing shunt springs 11, 12 and 13 to be operative. As the push bar 19 continues to be depressed, linkage plate 30 and control plate 31 continue to rotate clockwise until the release pin 51 in the control plate 31 strikes against holding pawl 21. The push bar is now depressed until stop 57 rests against plate 47, at the same time release pin 51 pushes holding pawl 21 out of engagement with a tooth such as 50 in holding gear 49. Simultaneously, with the rotation of control plate 31, movable pawl 43 is rotated, and it engages a tooth such as 56 in movable pawl gear 52 at the same time that the push bar reaches its limit when holding pawl 21 is disengaged from tooth 50 in holding gear 49. Spring motor 9 is now wound and locked, as the rotation of control plate 31 rotates shaft 28 which is fastened to one end of the spring motor. Movable pawl 43 and holding pawl 20 have locked the spring motor in its present state. Release finger 33 has also rotated away from holding pawl 22, so that the

holding pawl now rests on the upper edge of push bar 19. At the very instant of the initiation of the restoration of the push bar 19, while release pin 51 is keeping holding pawl 21 disengaged from tooth 50, holding gear 49 is allowed to rotate counter clockwise only a short distance and mesh tooth 50 tightly with the notch in holding pawl 20. As the push bar 19 is restored further, release pin 51 no longer bears against holding pawl 21, but the small amount of the aforementioned rotation has prevented holding pawl 21 from engaging holding gear 49 and the pawl now rests on the outer periphery of holding gear 49. Biasing spring 24 continues to exert force on linkage plate 30 and rotate it in a counterclockwise direction to restore push bar 19 due to the linkage connection between release pin 40 and notch 55. Release pin 40 travels along the indentation of control plate 31. Just before stops 59 on push bar 19 strike frame 1, release pin 29 strikes against holding pawl 20. At the instant stops 59 strike the frame, release pin 29 has forced holding pawl 20 back and disengaged its notch with the tooth 50 in holding gear 49, thereby releasing the mechanism for operation. At the same instant of release, holding pawl 22 engages notch 34 in push bar 19, and thereby prevents a reoperation of push bar 19 until control plate 31 is fully restored. As a result of the operation of pawl 20 spring motor 9 now causes drive gear 32, holding gear 49, movable pawl gear 52, and control plate 31 to rotate counterclockwise. As impulse wheel 17 is mounted on an auxiliary shaft and geared to the drive gear 32, it will rotate also. The teeth, such as 18 on the impulse wheel, will strike impulse arm 14, resulting in the opening and closing of the contacts on impulse arms 14 and 15, which thereby cause pulses to be transmitted in accordance with the number of teeth on the impulse wheel. Release finger 33 is rotated back with control plate 31 and at the instant the mechanism stops, after one complete rotation of the impulse wheel, finger 33 forces holding pawl 22 out of engagement with notch 34, releasing push bar 19 in preparation for a future operation.

Four teeth have been illustrated on the impulse wheel, but a lesser or greater number may be used, depending on the desired signal.

In the foregoing description, in order to start the operational cycle, the push bar 19 must be completely depressed so that stop 57 rests against plate 47. An incomplete depression or number of incomplete depressions of the push bar 19 will not lock the spring motor or cause a transmission of pulses.

Assuming that the push bar 19 has been depressed completely, then only partially restored and depressed again and repeated a number of times, no additional winding of the spring motor will occur, and no additional pulses will be transmitted, because the push bar must be completely restored to allow the release mechanism to function and permit the spring motor to unwind. If an attempt is made to depress the push bar 19, while the release mechanism and spring motor are functioning, it is stopped because release finger 33 has rotated away from its contact with holding pawl 22 and allowed the pawl to engage notch 34, thereby preventing further depression of the push bar until the mechanism has completed its operation and release finger 33 has rotated back and disengaged holding pawl 22 from notch 34.

It will be noted that the above arrangements

prevent a calling party from maliciously sending a false identification.

Having described my invention, what I consider to be new and desire to have protected by Letters Patent will be pointed out in the appended claims.

What is claimed is:

1. In an impulse transmitter comprising a rotatable shaft, a driving gear mounted on and free to rotate in only one direction about said shaft, an impulse wheel connected to said gear and rotatable therewith, a spring motor for rotating said shaft, a finger operated push bar, a control plate mounted on and secured to said shaft and rotated in response to the manual operation of said push bar for rotating said shaft to wind said spring motor, a first holding pawl normally engaging said gear to prevent rotation of said gear and operated in response to full depression of said push bar to disengage said holding pawl from said gear, a second holding pawl operated in response to the manual depression of said push bar for holding said gear and plate after the disengagement of said first holding pawl from said gear and for releasing said gear and plate in response to the restoration of said push bar to normal to permit said spring motor to rotate said plate, said gear, and said impulse wheel, a third holding pawl operated in response to the restoration of said push bar to normal position to prevent its reoperation, and a finger on said plate for releasing said third holding pawl to unlock said push bar in response to the rotation of said plate to normal.

2. In an impulse transmitter comprising a rotatable shaft, a driving gear mounted on and free to rotate in only one direction about said shaft, an impulse wheel connected to said gear and rotatable therewith, a spring motor for rotating said shaft, a finger operated push bar, a control plate mounted on and secured to said shaft and rotated in response to the manual operation of said push bar for rotating said shaft to wind said spring motor, a first holding pawl normally engaging said gear to prevent rotation of said gear and operated in response to full depression of said push bar to disengage said holding pawl from said gear, a second holding pawl operated in response to the manual depression of said push bar for holding said gear and plate after the disengagement of said first holding pawl from said gear and for releasing said gear and plate in response to the restoration of said push bar to normal to permit said spring motor to rotate said plate, said gear, and said impulse wheel.

3. In an impulse transmitter comprising a rotatable shaft, a driving gear mounted on and free to rotate in only one direction about said shaft, an impulse wheel connected to said gear and rotatable therewith, a spring motor for rotating said shaft, a finger operated push bar, a control plate mounted on and secured to said shaft and rotated in response to the manual operation of said push bar for rotating said shaft to wind said spring motor, a first holding pawl normally engaging said gear to prevent rotation of said gear and operated in response to full depression of said push bar to disengage said holding pawl from said gear, a second holding pawl having a normal position and a holding position and operated from its normal position to its holding position in response to the manual operation of said push bar, said spring motor

effective after disengaging said first holding pawl from said gear and at the initiation of the release of said push bar to partially rotate said gear until held by said second holding pawl in its holding position, said partial rotation rendering said first pawl ineffective to hold said gear until after a predetermined rotation of said gear, and means on said push bar for restoring said second holding pawl from its holding position to its normal position to permit said spring motor to rotate said plate, gear and wheel to transmit impulses.

4. In an impulse transmitter, a finger operated push bar, a control plate, a linkage device operatively connecting said control plate to said push bar in response to only the depression of said push bar to rotate said control plate, a spring motor wound to store energy in response to the rotation of said plate, a driving gear, a movable pawl for coupling said gear to said plate after rotation of said plate, means for holding said gear to prevent its rotation, and release means effective in response to the full restoration of said push bar for releasing said holding means to permit the energy stored in said spring motor to rotate said plate and said gear.

5. In an impulse transmitter, a finger operated push bar, a control plate rotated in response to the manual depression of said push bar, a spring motor wound to store energy in response to said depression, a driving gear coupled to said plate in response to the full depression of said push bar, means for delaying rotation of said plate and gear until said push bar is fully restored, means for operating said delaying means in response to the full restoration of said push bar to permit rotation of said gear and plate, a holding pawl effective on restoration of said push bar for preventing a reactuation of said push bar after its restoration, and a release finger on said control plate for operating said pawl to permit reactuation of said push bar in response to the completed rotation of said control plate.

6. In an impulse transmitter, a finger operated push bar, a spring motor wound to store energy in response to the manual depression of said push bar, a driving gear rotated by said spring motor in response to the restoration of said push bar, a holding pawl effective on restoration of said push bar for preventing a reactuation of said push bar after its restoration, and a release finger responsive to the rotation of said gear for operating said pawl to permit reactuation of said push bar.

7. In an impulse transmitter, an impulse wheel having a variable number of teeth, an energy storing device, a controlled finger operated push bar manually depressed for transmitting energy to said storing device, means for connecting said storing device with said impulse wheel, and means effective after full restoration of said push bar for releasing said energy to rotate said impulse wheel to transmit pulses in accordance with the number of teeth on said wheel.

8. In an impulse transmitter, an impulse wheel containing a variable number of teeth, a driving gear geared to said wheel, a finger operated push bar, a spring motor wound to store energy in response to a depression of said push bar, means for delaying the rotation of said gear and said wheel until said push bar is fully restored, means effective in response to the full restoration of said push bar for causing said spring motor to rotate said gear and to turn said wheel one complete revolution, and means controlled by the

number of teeth on said wheel for transmitting a corresponding number of pulses in response to the complete revolution of said wheel.

9. In an impulse transmitter, a finger operated push bar, a spring motor wound to store energy in response to the manual depression of said push bar, a holding pawl effective after depression of said push bar for preventing said spring motor from unwinding, a release means operative on restoration of said push bar for operating said holding pawl to release said energy, a first limiting means on said push bar to limit the amount of said depression, a second limiting means on said push bar to limit the amount of said restoration, said first limiting means determining the amount that said spring motor is to be wound, and said second limiting means stopping the restoration of said push bar at the instant said release means has operated.

10. In an impulse transmitter, a finger operated push bar, a slot on said push bar and a tooth on each side of said slot, a control plate having an indented portion of its periphery, a linkage plate

for operatively connecting said push bar with said control plate, a linkage pin mounted on said linkage plate, said linkage pin meshed between said teeth on said push bar and protruding into said indentation of said control plate, a biasing spring connected to said linkage plate, means effected by the depression of said push bar for moving said linkage pin against said control plate and rotating said plate, and means responsive to the action of said biasing spring for exerting force on said linkage plate and cause it to rotate to move said linkage pin along said indented portion of said control plate for restoring said push bar to normal.
